UNITED STATES PATENT OFFICE

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

LOCK FOR REVOCABLE TRANSFER MECHANISM

Application filed September 1, 1931. Serial No. 560,595.

This invention relates to improvements in revoking mechanism for weft replenishing looms and it is the general object of the invention to provide for positively revoking a 5 previously indicated transfer without interfering with the restoration of the magazine to normal condition by locking the trans- ferrer arm in down or transferring position.

In multicolor weft replenishing looms the 10 shuttle feeler and lay engaging latch on the trans- ferrer arm are connected together, usually by means of a top horizontal shaft, so that when the trans- ferrer is indicated the latch will be raised and the shuttle feeler simultaneously depressed to engage a misplaced shuttle. If the shuttle is not properly boxed 15 it will lift the shuttle feeler the effect of which is to lower the latch, so that the latter cannot have engagement with the bunter on the lay, thus preventing transfer. It has been customary in the past to rely upon 20 gravity to lower the latch, but in fast running looms it is found that the latch does not have time to fall out of the path of the bunter.

When a positive control is introduced between the shuttle feeler and the latch to afford means for lowering the latter quickly, some provision must be made for permitting the 30 return of the magazine to normal condition. In this connection it is to be understood that if a transfer takes place in proper manner the shuttle feeler will act to restore the magazine to its original unset condition. From this it 35 will be seen that both the positive depression of the latch and the resetting of the magazine are accomplished through the same device which effects these two results by operating at two different times.

40 When the lay reaches front center on a transferring beat the act of transfer is completed and the magazine parts are all reset back to normal with a single exception of the transfer mechanism. This is due to the 45 fact that the latch is engaged with the bunter and must maintain this engagement ordinarily until the lay moves back sufficiently to permit the trans- ferrer arm to be reset.

It is an important object of my present invention to provide means for locking the

trans- ferrer arm in down position at the completion of a transfer operation so that the latch will be held in relative forward position as the lay starts to move rearwardly. In this way the positive connection between the latch and the shuttle feeler will not be subject to any force acting to give the shuttle feeler another setting on the backward stroke of the lay.

In the usual operation of the trans- ferrer arm it will reach a position low enough to traverse the path of some part of the lay, and it is a further object of my invention to provide means for locking the trans- ferrer at a point a short distance above its lowest position so as to avoid interference with any part of the lay.

The particular means for unlocking the trans- ferrer arm as set forth herein includes a trip to be struck by the lay as the latter reaches its first rear position after transfer. In this connection it is a further object of my invention not only to effect release of the lock by the lay, but also to give the lock an additional movement derived from the trans- ferrer arm as the latter is restored to normal so that the trip will be held out of the path of the lay during normal running of the loom.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is a side elevation of a multicolor weft replenishing mechanism showing my invention in normal position and viewed from the interior of the loom, certain parts being in section.

Fig. 2 is a view similar to Fig. 1 but with the parts shown in transfer position.

Fig. 3 is an enlarged front elevation taken in the direction of arrow 3, Fig. 2.

Fig. 4 is a horizontal section on line 4—4 of Fig. 1, and

Fig. 5 is a vertical section on line 5—5 of Fig. 4.

Referring to the drawings, I have shown a

four-cell stationary magazine of the usual type and designated at M. The magazine has a foot 10 which rests on the breast beam 11 of the loom and has a plate 12 from which 5 extend a plurality of vertical parallel flanges 13 defining four reserve bobbin compartments 14.

A fixed stud 15 has pivotally mounted thereon a transferrer lever 16 having a horizontal arm 17 and vertical arm 18. The latter has pivotal connection as at 19 with a latch holder 20 to which is secured a latch 21. The latter is adapted to engage a bunter 22 on the lay L in the usual manner.

15 A shuttle feeler 23 is pivoted above the lay as at 24 to a rear fixed part of the magazine frame and has connection as at 25 with an upwardly extending control or connector rod 26. The connector rod 26 is attached at the 20 upper end thereof to a rocking lever 27 which oscillates about an axis determined by bearings 28 formed as a fixed part of the magazine frame. This lever comprises a right hand element 29 as viewed in Fig. 1 which is 25 secured to a horizontal shaft 30 turning in the bearings, while the rear or left hand part of the lever includes an element 31 also secured to the shaft. A second vertical control rod 32 is attached at the element 31 and acts when 30 the lever 27 is oscillated on a working stroke to move downwardly and have connection at the lower end thereof with the latch holder 20 to elevate the latch.

The matter thus far described is substantially the same as shown in Patents No. 1,030,748 and No. 1,786,688. Certain mechanism has been omitted for the sake of clearness, but it is to be understood that the magazine, except as pointed out hereinafter, is of the 40 usual multicolor type and acts to deliver a bobbin of selected color to be inserted in the shuttle S when exhaustion is indicated. Preparatory to transfer the lever 27 will be oscillated by mechanism not shown but well 45 understood to lower the rod 26 and thereby move the shuttle feeler 23 downwardly where it may engage a misplaced shuttle to revoke transfer, or to engage the box back B to reset the magazine. At the same time the shuttle 50 feeler is depressed the latch 21 will be raised through connections to be described more particularly hereinafter, but operating at substantially the same time in the cycle of the loom as that existing in present magazines.

As previously stated, my invention relates to means for positively revoking a previously indicated transfer should the shuttle fail to be properly boxed, and in carrying my invention into effect I provide the latch holder 20 as shown in Figs. 1 and 2 with a forward extension 40 defining a short slot 41. Extending upwardly from the slot and forwardly is an inclined finger 42 the lower 65 edge of which merges with the upper part of

the slot 41. A stud 43 extends into the slot and is carried by a rod head 44 formed on the lower end of the rod 32. The stud 43 is adapted for engagement with the extension 40 and the walls of the slot 41 and also the 70 lower surface of the finger 42.

One of the tie rods 50 of the magazine has pivoted thereto a lock lever 51 having a shoulder or notch 52 which is positioned to engage an upper relatively sharp corner or edge 53 of the transferrer arm. As shown in Fig. 4, a light torsion spring 54 is connected at one end to a collar 55 fixed to the tie rod and at the other end to the lock acting to move the latter in a clockwise direction as viewed in Fig. 2 so as to urge the notch or shoulder 52 in a direction toward the transferrer arm. A stop pin 56 serves to arrest movement of the lever 51 around the tie rod. A rearwardly extending wire 57 is threaded into the lock lever to be adjustable relatively thereto and has the rear end bent downwardly as at 58 to have engagement with the box back B.

The front of lever 51 is provided with an inclined cam face 60 positioned and formed so as to engage a corresponding face 61 on the transferrer arm when the latter is in raised position. A relatively heavy torsion spring 62 of the usual form acts in well-known manner to hold the transferrer arm yielding- 55 ly in the raised position indicated in Fig. 1. This heavy spring 62 is of sufficient strength to overcome the light spring 54 and holds the lock lever as shown in Fig. 1 with the bent end 58 of the wire 57 disposed slightly behind the rearmost position of the box back B.

In operation, so long as sufficient weft in the running shuttle is present, the parts will remain in the position shown in Fig. 1, the lay moving back and forth under the magazine. When an exhausted shuttle which has previously given indication of weft exhaustion is under the magazine, mechanism not shown but well understood will come into play to oscillate the lever 27 in such a direction as to depress the shuttle feeler 23 and raise the latch 21. These operations take place when the lay is in a relatively rearward position. As the lay advances one of two conditions will result, either transfer will take place in the normal manner, or the indicated transfer will be revoked and prevented.

If a normal transfer takes place the shuttle will be boxed sufficiently to clear the shuttle feeler and the bunter will engage the latch 21 to move the latter forwardly. As the lay continues its advance the slot 41 will move forwardly with respect to the pin 43 until the parts assume the position shown in Fig. 2. As the lay reaches its extreme forward position the box back B will engage the shuttle feeler to raise the latter and this will result in the simultaneous lifting of stud 43. The inclined finger 42, however, has by this time moved far enough forwardly so that it 120

will not interfere with the upward movement of said stud, and the top lever 27 may be reset to its normal position.

As soon as the transerrer arm nears its lowest position surface 61 will move away from surface 60 and the corner 53 will pass under the notch or shoulder 52, thereby freeing the lock lever 51 to permit the same to respond to the force of spring 54 and move in such a direction as to place the shoulder 52 over the edge 53. This movement on the part of lever 51 also advances the bent end 58 into the path of movement of the box back B.

As the lay starts its rearward movement the latch will be held in contact with the bunter by the spring 62 for a short distance, and the upward movement of the transerrer arm incident to the rearward movement of the lay will bring about engagement of the edge 53 with the shoulder or notch of the lock lever, whereupon the transerrer arm will be locked against further upward movement. The extent of upward movement of the transerrer arm before being locked can be varied by changing the position of the notch or shoulder 52, but in any event the lower part of the transerrer arm will be held high enough to clear the lay as the latter moves rearwardly.

It is common practice in the looms to which my invention more particularly applies to have the latch released by the bunter when the lay has moved approximately one-quarter of its distance from front to back position, so that when the lay has moved back approximately one and one-half inches the latch 21 will be free to move down around pivot 19 as a center. By inspecting the relation of the parts shown in Fig. 2 it will be seen that the inclined finger 42 can move around the pivot pin 19 without engaging the stud 43. The purpose of this relation is to permit the latch to fall to its low position without interfering with or communicating force to the oscillating lever 27. The latch therefore drops by gravity without disturbing the shuttle feeler 23 or lever 27.

In connection with the relations just described it is of consequence to notice that the lay moves a considerable distance after releasing the latch before the box back B engages the bent end 58 of the wire 57. As the lay reaches its extreme rearward position, however, the wire will be struck to rock the lock lever 51 slightly about its tie rod support, thereby releasing the transerrer lever so that the heavy spring 62 will raise the surface 61 along and against surface 60. This upward movement of the horizontal part 17 of the transerrer arm takes place after the latch has moved down to its low position by gravity and there is no chance for the force of spring 62 to be exerted against the lever 27.

If the second of the previously mentioned conditions exists and the shuttle is not prop-

erly boxed, the shuttle feeler 23 will be raised in the usual manner by engagement with the misplaced shuttle and a positive upward force will be exerted against the top of slot 41. There will result a quick positive downward movement of the latch to prevent engagement of the bunter on the lay. It is seen therefore that the rate at which the loom is running and the transerrer latch is moved to clear the bunter at the time of revocation is proportional to the speed of the loom, that is, the quicker the loom runs the quicker it will revoke.

From the foregoing it will be seen that I have provided means for positively revoking a previously indicated transfer of a multi-color weft replenishing mechanism without interfering with the normal transfer. It will also be seen that the result just described is achieved by locking the transerrer arm in down position a sufficient length of time to permit the lay to move out of controlling relation with respect to the transerrer latch. As a matter of convenience the latch is released by the lay when the latter is in a relatively forward position, while the transerrer arm is not released or unlocked until the lay is in its rearward position. It is also seen that the transerrer arm acts when in its up or raised position to hold the bent end 58 of the wire out of the path of the lay.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom having a lay and a shuttle feeler, a transerrer mechanism having a latch to be operatively related to the shuttle feeler during forward movement of the lay until the latter advances to a given position and to be disconnected from said shuttle feeler during the remainder of the forward motion of the lay, engagement of the lay with the latch effecting transfer, and means operative on a transferring pick to disconnect the latch from the lay before the latter reaches the said given position in the backward movement thereof.

2. In a weft replenishing loom having a lay and a shuttle feeler, transfer mechanism having a latch to be operatively related to the shuttle feeler before the lay reaches a given position in its forward motion and to be disconnected from the shuttle feeler after the lay passes said position in its forward motion, the latch to engage the lay to effect the transferring operation, and means operative after the completion of a transferring operation to prevent the latch from following the lay as the latter moves away from the transfer position.

3. In a weft replenishing loom having a

lay and a shuttle feeler, transfer mechanism having a latch to be operatively related to the shuttle feeler while the lay is moving through a revoking range of motion and to be disconnected from the shuttle feeler during the transferring range of motion of the lay, the latch to engage the lay during the transferring range to effect a transferring operation, and a lock operative substantially upon completion of the transferring operation to prevent the latch from remaining in engagement with the lay when the latter moves out of the transferring range of motion.

4. In a weft replenishing loom having a lay and a shuttle feeler, transfer mechanism having a latch to be operatively related to the shuttle feeler while the lay is moving through a revoking range of motion and to be disconnected from the shuttle feeler during the transferring range of motion of the lay, the latch to engage the lay during the transferring range to effect the transferring operation, and a lock rendered operative by movement of the transferring mechanism to hold the latter adjacent the position it assumes upon completion of the transferring operation to prevent the latch from moving with the lay out of the transferring range of motion of the lay.
5. In a weft replenishing loom having a lay and a shuttle feeler, transfer mechanism having a latch to be operatively related to the shuttle feeler while the lay is moving through the revoking range of motion and to be disconnected from the shuttle feeler during the transferring range to effect the transferring operation, means operative after the completion of a transferring operation to prevent the latch from following the lay into the range of motion corresponding to the revoking range, and means operative after the lay moves away from the transferring range to render the latch capable of returning to normal position.
6. In a weft replenishing loom having a lay and a shuttle feeler, transfer mechanism having a latch to be operatively related to the shuttle feeler while the lay is moving through a revoking range of motion and to be disconnected from the shuttle feeler during the transferring range of motion of the lay, the latch to engage the lay during the transferring range to effect the transferring operation, a lock rendered operative by movement of the transferring mechanism to hold the latter adjacent the position it assumes upon completion of the transferring operation to prevent the latch from moving with the lay out of the transferring range of motion of the lay, and means operative by the lay to unlock the transfer mechanism after the lay moves out of the transferring range on its rearward stroke.
7. In a loom having a lay, a transfer mechanism, means to connect the mechanism and

lay as the latter moves in one direction to cause the transfer mechanism to have a transferring operation, and means to hold the transferring mechanism locked in approximately the position it occupies at the completion of the transferring operation, and while the lay is moving in the opposite direction.

8. In a weft replenishing mechanism having provision for positively revoking a transfer, a transerrer arm, means to set the transerrer arm for transfer, a lay to engage a part of the transerrer arm when the latter is set to effect transfer, and means to lock the transerrer arm after the lay has given the transerrer arm a transferring movement.

9. In a multicolor weft replenishing loom capable of revoking a previously called transfer, a regularly moving element, transfer mechanism, a latch to be engaged by the element to transmit a force from the latter to the mechanism to give said mechanism a transferring operation, and a lock to hold the transferring mechanism approximately in the position it assumes upon completion of the transferring operation, the latch being released by the lay and movable with respect to the mechanism during the time that the latter is locked.

10. In a multicolor weft replenishing loom capable of revoking a previously called transfer, a regularly moving element, transfer mechanism, a latch to be engaged by the element to transmit a force from the latter to the mechanism to give said mechanism a transferring operation, a lock to hold the transferring mechanism adjacent the position it assumes upon completion of the transferring operation, the latch being released by the lay and movable with respect to the mechanism during the time that the latter is locked, and means to render the lay effective to unlock the transfer mechanism after the latch has been released by the lay.

11. In a loom having a lay, transfer mechanism to be operatively related to the lay to have a transferring operation, and means to lock the transferring mechanism after completion of a transferring operation and maintain said mechanism locked as the lay moves away from transfer position.

12. In a loom having a lay, transfer mechanism to be operatively related to the lay to have a transferring operation, means to lock the transfer mechanism adjacent the position it assumed upon the completion of a transferring operation; and means to thereafter unlock said mechanism.

13. In a loom having a lay, a transfer mechanism to be operatively related to the lay to have a transferring operation, means to lock the transfer mechanism after completion of a transferring operation with the lay in a given position, and means effective to release

the transfer mechanism when the lay has moved away from said given position.

14. In a loom having a lay, a transfer mechanism to be operatively related to the lay to have a transferring operation, means to lock the transfer mechanism upon completion of a transferring operation with the lay in a given position, a device operative by the lay and effective when the lay has moved away from said given position to unlock the transfer mechanism, and means effective when the transfer mechanism returns to normal position to move the releasing device out of the path of the lay.

15. 15. In a weft replenishing loom having a lay movable back and forth therein, a transerrer arm, means to give the transerrer arm a transferring movement during movement of the lay in one direction, means to there-
20 after lock the transerrer arm, and a subsequently active means operative when the lay is moving in the other direction to unlock the transerrer arm.

16. In a weft replenishing loom, a lay hav-
25 ing beating-up and return strokes, a transfer mechanism including a latch, means to set the latch for engagement with the lay when a transfer is called, positively acting means operative at a given point in the beating-up
30 stroke of the lay to move the latch positively out of operative relation with respect to the lay if the shuttle is improperly boxed, the lay and latch having operative engagement at a later point in the beating-up movement of
35 the lay if the shuttle is properly boxed, means thereafter effective to lock the transerrer arm adjacent the position it assumes at completion of the transferring operation until the lay on its return stroke moves out of
40 operative relation with respect to the latch, and means subsequently operative to unlock the lay.

In testimony whereof I have hereunto affixed my signature.

45 ALBERT A. GORDON.
